**SAFETY RAZOR BLADE HOLDER WITH
SELF-CLOSING OPERATION**

John Guardino, New York, N. Y.

Application October 22, 1954, Serial No. 464,045

3 Claims. (Cl. 30—60.5)

The invention relates to an improved double razor blade holder and one of its objects is to provide a holder for a double edge razor blade which can be opened by the movement of the holding hand, and which will close automatically to clamp the blade for shaving.

Another object of the invention is the provision of a razor blade holder having blade clamping members hinged to open upwardly and outwardly simultaneously, with a plunger rod for opening both blade clamping members, a compression spring for moving the rod to closing position, and a knob mounted to slide on the handle of the razor blade holder which is coupled directly to the spring actuated plunger rod, so that the holding person can with the same hand which holds the razor open both blade clamping members by a short upward finger movement, cleanse the used razor blade, shake off surplus water and then allow the spring actuated rod to close the blade clamping members.

A further object of the invention is to provide means for subjecting the spring actuated plunger rod to screw pressure when it has been shifted to closed position, so that maximum pressure is developed on the blade clamping plates or members.

With the above and other objects in view, the invention comprises certain new and useful constructions, combinations and arrangements of parts, clearly described in the following specification and fully illustrated in the drawings accompanying this application, in which:

Fig. 1 is an end elevation of a razor blade holder constructed in accordance with my invention, shown enlarged, and showing the blade clamping members in closed position.

Fig. 2 is a vertical sectional view thereof, showing the operating plunger rod and the blade clamping members in open or raised position.

Fig. 3 is a top plan view, showing the clamping plates in open positions.

Fig. 4 is an end elevation, showing the razor blade holder closed, in normal scale or full size.

Fig. 5 is a side elevation of the handle tube, showing the vertical or longitudinal slot thereof.

Fig. 6 is a similar view of a modified form of the handle tube.

Referring to the accompanying drawings which illustrate the practical embodiment of my invention, 10 designates a handle tube having a spool shaped bushing or extension 11 coupled thereto, as by the screw threads 11a.

To the upper end of the extension or bushing 11 a frame base 12 is secured, by the swaged eyelet or fastener 11b formed on the extension or bushing 11. This frame base is provided with the usual parallel curved edges 13 and 14, which ride against the face of the person to be shaved.

In the axial bore 11c of the extension or bushing 11 a rod section 15 is disposed, and the upper end of this rod section is bifurcated at 15a and is secured to the blade centering bar 16, which is movable with the rod section. The rod section 15 may have a swivelled connec-

tion at 17 with the lower rod section 18, which is provided on its lower end with collar 19, secured thereto by the cross pin 20.

The collar 19 has a free sliding fit in the handle tube 10, and on the outer side of the handle tube a cylindrical sleeve 21 is slidably mounted, and the outer ends of the cross pin 20 slidably extend through the aligned slots 22 and 23 on diametrical opposite sides of the handle tube, and pass through the wall of the sleeve 21 and are headed 10 against the outer surface of this sleeve.

The upper end of the sleeve 21 is formed with an external bead 21a and provided with an external button 24, fixed thereto, as by the pin 24a, and shown to be small in diameter. The bead forms a thrust shoulder for manually pushing the sleeve upwards on the handle tube. Any form of fixed connection, as brazing or hard soldering, may be used for securing the button in place.

A coil spring 25 is mounted on the lower rod section 18, and at its lower end engages the collar 19 and at its upper end engages the washer 26, disposed against the inner end of the bushing or extension 11. This spring exerts pressure to force the collar 19 downwardly, and as the cross pin 20 connects this collar to the rod section 18 and to the external sleeve 21, through the aligned slots 22 and 23 of the handle tube, the sleeve 21 will also be forced downwardly.

The centering bar 16 is connected at one end to the end link 27 of the razor holder, and at the other end to the end link 28. The link 27 is pivotally connected to the lever ends 29 and 30 of the blade clamp plates 31 and 32, and the link 28 is pivotally connected to the lever ends 33 and 34 of the same clamp plates, all in the usual manner.

The coil spring 25 normally holds the clamp plates in closed positions, as shown in Fig. 4, but by manually pushing the sleeve 21 upwardly on the handle tube 10, the central rod will be moved longitudinally to raise the centering bar 16 and thereby tilt both blade clamp plates upwardly and outwardly to open positions.

The external sleeve 21 is long enough to always cover the two side slots of the handle tube, and the lower end of this handle tube is provided with a plug 36 which is enlarged to provide a hand rest to receive the thrust of the hand when the sleeve 21 is shifted upwardly to open the razor blade holder.

The handle tube may be formed with a slot 35 on each side thereof, having a short lateral and diagonal extension 35a on its lower end, so that by slightly twisting the sleeve 21 the pin 20 will ride in these offset slot portions and additional pressure will thus be imposed on the clamp plates to hold the razor blade in place.

My invention provides a razor blade holder which may be opened by one hand, and by the same hand which uses the razor holder for shaving, by simply pushing the external sleeve or its button, against the resistance of the enclosed coil spring, so that the holder may be fully opened to flush soap and hair ends from the holder, and then to replace the blade with a fresh blade.

This self-closing razor holder utilizes the hinged blade clamping plates and operating links, basically disclosed by an expired patent, to provide a one hand operated razor holder which will automatically close, to safely protect the enclosed razor blade, so that it cannot be injured by accidental contact with other objects, or displaced from its correct centered position under the clamping plates.

It is understood that various changes in the details of construction, their combination and arrangement, may be made in carrying out the invention defined by the claims.

Having described my invention, I claim as patentable:

1. The combination of a double edge razor blade holder having a tubular handle and a holder base secured to the upper end of the tubular handle, clamping plates, links

disposed at the opposite ends of the base and having pivotal connection with the clamping plates to rock the same, a rod sliding through the handle and having operating connections with the links to open and close said clamping plates; of a sleeve slidable on the handle, a spring within the handle for actuating the rod downwardly in the handle, and a pin having its outer ends secured to the sleeve and sliding longitudinally of the handle, said handle being formed with opposing slots through which said pin freely extends for sliding movement.

2. The construction set forth in claim 1, the handle having longitudinal slots provided with diagonal lateral end portions and the pin being movable into said diagonal end slot portions to lock the clamping plates in clamping position.

3. The combination with a double edge razor blade holder having a tubular handle and a blade holder base secured to the upper end of the handle, clamping plates pivotally connected with the base to clamp a double edge razor blade against the base, a rod sliding in the handle and having operative connections with the clamping plates

to move the said clamping plates from blade clamping position to raised open position and to return the clamping plates to blade clamping position, a spring enclosed by the tubular handle for moving the rod downwardly to close the clamping plates to blade clamping position, a pin connected transversely to the rod, the tubular handle being formed with a slot through which the pin projects, and a member mounted on the pin and slidable on the outside of the handle and providing means for the manual shifting of the rod against the pressure of the spring to raise the clamping plates to blade releasing raised position, said spring reacting to force the rod downwardly when manual pressure is released to automatically close the clamping plates to blade clamping position.
